(57) **CLAIM**

I claim the ornamental design for a portable storage unit with bins, as shown and described.

DESCRIPTION

FIG. 1 is a side, top perspective view of the portable storage unit with bins of the present invention.

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken lines showing portions of the design form no part of the claimed invention.
